UNITED STATES PATENT OFFICE.

EDWIN E. SLICK, OF PITTSBURG, PENNSYLVANIA.

HOTBED FOR ROLLING-MILLS.

No. 846,761.

Specification of Letters Patent.

Patented March 12, 1907.

Application filed November 9, 1903. Serial No. 180,305.

To all whom it may concern:

Be it known that I, EDWIN E. SLICK, of Pittsburg, Allegheny county, Pennsylvania, have invented a new and useful Hotbed for Rolling-Mills, of which the following is a full, clear, and exact description, reference being had to the accompanying drawings, forming part of this specification, in which—

Figure 1 is a top plan view showing a portion of my improved hotbed, the bed proper being broken away in the lower half of the view. Fig. 2 is an irregular vertical cross-section on a larger scale. Fig. 3 is a central longitudinal section showing a central portion of the table, and Figs. 4 and 5 are respectively a partial plan view and a vertical cross-section showing a part of the central portion of a modified form of the invention.

My invention relates to the hotbeds employed for receiving the rolled sections from a rolling-mill and is designed to increase the capacity of the bed for handling the rolled metal and increase the rapidity of the operations.

The invention consists in providing a guiding-runway in which the metal is received, this runway having side guides in connection with means for either raising the metal from the runway and moving it sidewise or moving the side guides vertically and then moving the metal sidewise.

It further consists in pusher mechanism for acting upon the metal to move it sidewise, which pusher mechanism contacts with the rolled piece throughout its length, or substantially so. This is of special advantage in connection with metal of small cross-section—such as small angles, channels, &c.—in which the metal is liable to be bent by the pushers heretofore used.

The invention also consists in using a receiving-runway which is stationary so far as lateral motion is concerned in connection with a side pusher, which moves the metal from the runway sidewise upon the hotbed, and, further, in the above combination, where hotbeds are provided on each side of the runway, the pusher being adapted to move the metal to either side.

It further consists in the construction and arrangement of parts, as hereinafter more fully described, and set forth in the claims.

In the drawings, referring to the form of Figs. 1, 2, and 3, 2 represents a longitudinal guiding-runway, which is in front of the fin-

ishing-pass of a rolling-mill, this runway having side guiding portions which hold and guide the metal as it is fed forward. In this form the runway is stationary and is supported upon a longitudinal box-girder 3, 60 mounted upon a foundation 4. The runway is of hollow box form, as shown in Fig. 2, and is provided with transverse recesses or depressions 5, through which the shoes for the pushers move transversely. The runway 2 is disposed centrally of the hotbed, which is shown as consisting of oppositely-inclined separated bars 6 6, extending from the runway to lines of feed-rollers 7 7, located at the opposite sides of the bed. The 70 pusher for moving the metal sidewise upon the hotbed consists of a continuous section, which is shown as formed of a channel 8, bolted to the separated shoes 9. These shoes are spaced at suitable intervals apart 75 between the bars 6 and are provided with outwardly and downwardly inclined surfaces 10 10, extending from the channel-section. Some of these shoes are clamped to transversely-extending wire ropes or flexible connections 11, which extend over central sheaves or pulleys 12 and also over end pulleys or sheaves 13, to which the ends of each rope are secured, as shown at 14 in Fig. 2. Each set of pulleys 13 is mounted upon a 85 longitudinal shaft 15, and these shafts are provided at mid-points of their length with chain-pulleys 16, to which are secured the ends of chains 17, secured, through turn-buckle connections 18, to a cross-head 19. 90 The cross-head 19 is centrally secured to the inner ends of the plungers 20, moving in hydraulic cylinders 21. The cylinders 21 are preferably single acting and are controlled by suitable valve mechanism, through which 95 the shafts 15 may be rotated in either direction. Some of the shoes 9 are not so connected to the wire ropes, but are merely bolted to and carried by the pusher. The rollers 7 are mounted in suitable bearings upon longitudinal beams 22, carried upon supports 23 over the shafts 15 and beneath the ends of the bars 6. The shoes 10 are preferably transversely beveled or inclined on their wings toward the entering side of the metal, 100 so that if the pusher happens to be in a position near the center of the table, where the incoming metal would contact with the wings, the end of the entering metal will not 105 strike the square side of the wing and cause 110

injury to the apparatus. These inclined faces are shown at 24 in Fig. 3.

In the operation of the apparatus the metal is fed forward from the rolling-mill 5 into and along the runway, by which it is guided and held in place. The valve mechanism of the cylinders 21 is then actuated to move the pusher 8 sidewise of the bed. As this pusher approaches the runway the inclined wings will lift the rolled piece, and the outer side face of the channel 8 will then push it sidewise out of the runway. If a series of sections are retained on either side of the runway, the pusher will actuate the group and 15 move the outer one upon the set of rollers 7 at such side. It will be noted that the metal is properly received in the stationary runway irrespective of the position of the pusher, and the pusher may then be actuated to 20 move the metal to the opposite side of the bed from that at which the pusher is resting when the piece enters.

In the form of Figs. 4 and 5 the runway consists of a channel 25, with the flanges projecting downwardly, and the side guides consist of separated tilting sections 26, arranged in pairs. Each of these sections is of lever form, carried by a shaft or rod 27 and having a counterweight 28. Each section also has a lateral wing 29 with an inclined upper edge. In this form the pusher consists of a plain channel-section 30, without wings or inclined shoes, and as it approaches the guides in its lateral movement it rides up over the inclined wings and depresses both sets of guides which are connected by the rods or shafts 27. The side guides will thus be forced down through slots at the sides of the central channel, and the pusher will then 35 force the rolled section sidewise over the depressed guides and upon the hotbed proper. After the pusher has passed the wings of the guides the counterweights will swing the guides back to their raised position, so that the next piece will be properly guided and held in the runway.

The advantages of my invention result from the use of a stationary runway which is always in position to receive the metal and is 50 provided with side guides to hold it in place and prevent its curving outwardly to either side, and further from the use of a pusher which is move bodily and sidewise of the bed and which removes the metal from the runway and carries it onto the bed. They further result from the substantial continuity of the pusher, which prevents bending of pieces of small cross-section during the pushing operation.

60 The metal may be received upon the hotbed no matter what the position of the pusher. The capacity of the table is therefore increased, and the metal may be handled rapidly.

65 The form and arrangement of the table,

the runway, the pusher mechanism, &c., may be varied widely without departing from my invention.

I claim—

1. A hotbed having a stationary runway 70 with side guides, mechanism for releasing the metal from the guides, a pusher, and mechanism for moving the pusher bodily and sidewise in a non-circular path parallel to the bed to move the metal from the trough onto the 75 bed, said pusher being arranged to move a group of the sections lying on the bed; substantially as described.

2. A hotbed having a stationary runway with stationary side guides, a substantially 80 continuous pusher and mechanism for moving the pusher bodily and sidewise in a non-circular path parallel to the bed to move the rolled section out of the runway and laterally on the bed; substantially as described. 85

3. A hotbed having a stationary runway with side guides, mechanism for releasing the metal from the guides, a movable pusher, and mechanism for moving the pusher bodily and sidewise in a non-circular path parallel to 90 the bed to push the metal sidewise from the runway; substantially as described.

4. A hotbed having a stationary runway with fixed side guides, a pusher having lifters, and mechanism for moving the pusher 95 bodily and sidewise in a non-circular path parallel to the bed to lift the section and push it from the runway onto the hotbed; substantially as described.

5. A hotbed having a stationary runway 100 with stationary side guides, a pusher having inclines arranged to lift the metal over the guides and mechanism for moving the pusher bodily and sidewise; substantially as described. 105

6. A hotbed having a central stationary runway with side guides, a longitudinal pusher having inclined wings on both sides thereof and mechanism for moving the pusher sidewise in either direction to lift the metal out of the runway and move it to either side thereof; substantially as described.

7. A hotbed having a central runway 115 with transverse grooves or slots, a pusher having inclined wings arranged to move through the slots and lift the metal over the guides and mechanism for moving the pusher bodily and sidewise; substantially as described. 120

8. A hotbed having a central runway, a longitudinal substantially continuous pusher with lifters on each side thereof and flexible connections arranged to move the pusher laterally in either direction; substantially as described. 125

9. A hotbed having a central fixed runway with fixed side guides, supporting-bars extending laterally on both sides of the runway, said runway having transverse grooves. 130

or slots, a laterally-movable pusher having lifters secured on both sides thereof and mechanism for moving the pusher in either direction to lift the metal from the guideway and move it laterally on the bed; substantially as described.

10. A receiving-bed having a stationary runway provided with side guides, mechanism for moving the metal and guide vertically relative to each other, a pusher, and means for reciprocating the pusher in alternate directions past the runway, substantially as described.

11. A receiving-bed having a runway provided with side guides, mechanism for moving the metal and guides, vertically relative to each other, a pusher adapted to form a continuous contact with the metal, substan-

tially throughout its entire length, and mechanism for moving the pusher sidewise.

12. A receiving-bed comprising a central runway with stationary portions to support the metal and side guides on each side thereof, hotbeds on both sides of the guide portions, a substantially continuous pusher, and mechanism for moving the pusher bodily sidewise in both directions to release the metal from the side guides and move it from the runway; substantially as described.

In testimony whereof I have hereunto set my hand.

EDWIN E. SLICK.
